CABINET

Herbert E. Mills, Detroit, Mich., assignor to Borg-Warner Corporation, a corporation of Illinois

Application July 17, 1936, Serial No. 91,050

8 Claims. (Cl. 312—1)

This invention relates to improvements in stoves and particularly to a light, clock and condiment set therefor.

The principal object of this invention is to provide a convenient utility set adapted for use in conjunction with a cabinet or the like and made up of several parts which may optionally be combined as a unit, but which, if not combined, will have as much utility as otherwise.

5 Another object of the invention is to provide a light, clock, and condiment set which is adapted to be assembled to the back of a gas or an electric range, said set to be provided preferably with a clock, a light, and a plurality of condiment receptacles, the use of any or all parts included within this invention being optional.

Another object of the invention is to provide a light, clock and condiment set which is made up of a plurality of parts which are interchangeable, 20 easily assembled, easily disassembled, and inexpensively manufactured, said assembly being adapted to be supported preferably by the back of an ordinary make of stove.

Another object of the invention is to provide 25 an inexpensive, though attractive, light, clock and condiment set which can be assembled without difficulty or damage to a stove which need not be altered in any way in order to operatively support such set, the combination of the parts of this invention being interchangeable and the use of any or all being optional.

Another object of this invention is to utilize 30 the supporting means of a stove or cabinet for supporting a combination of illuminating means, condiment holding means, time-telling means, or other means normally useful in the kitchen.

It would not be practical to manufacture a stove with a light, clock and condiment set permanently attached thereto, for many buyers 35 would not be willing to meet the extra cost thereof. However, a stove can be supplied with a few additional holes in the back panel thereof, and those holes need never be used if the buyer does not find it convenient to equip his stove 40 with a set such as that embodied in this invention.

This invention contemplates the provision of a 45 cabinet construction, preferably a stove, comprising a rear stove panel with means therein for attachment thereto of a bracket or holding means for supporting the structure herein disclosed. Said structure preferably comprises a supporting means for a condiment receptacle, or plurality thereof, a supporting means for a clock 50 or other useful kitchen instrument, and a support-

ing means for an illuminating means. It is intended that these means be used in combination, or individually, as the case may be.

The parts comprising this invention are separately constructed, but adapted to be used in combination if so desired. They are individually very low in cost, and their replacement is of little financial consequence in comparison to the utility derived therefrom. Their construction is simple, and they afford, therefore, little or no difficulty in assembly or disassembly. The unit as a whole attractively presents an inexpensive structure capable of performing several duties, and each part, if used separately, will as efficiently perform its individual duty.

For a better understanding of the advantages thereof, reference may be had to the following specification taken in conjunction with the accompanying drawings of which there are two sheets and in which:

Fig. 1 is a perspective view of a stove, the extreme lower portion of which has been omitted, showing the invention in a general manner;

Fig. 2 is a front elevational view of the light and condiment set with a portion of the rear panel 25 of the stove, to which it is connected, partially shown;

Fig. 3 is a side elevational view, somewhat enlarged, taken on the line 3—3 of Fig. 2;

Fig. 4 is a side elevational view taken along line 4—4 of Fig. 2;

Fig. 5 is a rear elevational view taken along line 5—5 of Fig. 3; and

Fig. 6 is a perspective view of the lamp support, partially broken away at the lower portion 35 thereof.

A stove 10 of the gas or electric type is normally provided with a heat control panel generally indicated at 11. Handles 12 and a heat control assembly 13 are normally disposed outwardly of 40 said panel 11. Directly below panel 11 is one of a plurality of drawers 14 such as are usually provided in a stove and disposed to the right thereof is a conventional oven 15. The main stove top is indicated at 16 and is provided with a burner 45 box cover 17. The visible portion of the backguard or rear panel of the stove is indicated at 18. Generally indicated as being supported by the back of panel 18 is a clock support 19 with a clock 20 seated therein. A lamp bracket 21 is 50 shown as being disposed behind support 19 and supporting a lamp assembly generally indicated at 22. Disposed on either side of support 19 and behind panel 18 is a plurality of condiment receptacles generally indicated at 23 and 24. 55

It is to be noted that the detailed description of the parts of stove 10 is in no way essential to this disclosure, for stove 10 could merely be a cabinet or a work table. The description, therefore, is to be taken as explanatory rather than definitive.

Clock 20, adapted to be supported by clock support 19, is provided with lugs 31' projecting from said clock and resting upon a part of support 19. Said clock is also provided with controls generally indicated at 25.

Clock support 19 is provided with rearwardly extending flanges 19' at either side thereof effective for concealing the back portions of the light and condiment set from view. Lugs 26 extend forwardly from the lower portion of clock support 19 and lugs 27 project upwardly from an intermediate portion of said clock support; these lugs 26 and 27 are adapted to cooperatively engage portions of the back or splash panel 18 to secure the support in position. A plurality of holes 28 are provided in the clock support 19 adjacent its lower end to receive stove bolts 36; a hole 29 is provided in the upper portion of said clock support 19 for the reception of stove bolt 44. A hole 30 is disposed near the center of clock support 19 and above the line of contact between the back panel 18 and the clock support 19, and receives a lamp switch 52. At the top of support 19 are two equally spaced cutaway portions 31.

The stove bolts 36 serve to secure a removable metal bracket 32 to the rear of the support 19, the support 19 projecting downwardly into engagement with a stove frame member 18'. The lower portion of bracket 32 is secured to the frame 18' by means of a bolt 35.

A metal bar 38, shaped to provide a plurality of semi-circles, with a large portion of the center thereof being disposed behind clock support 19 and supported from below at the center thereof by the top of bracket 32, has a slot in its top at each end for receiving the downturned top portion of the stove rear panel 18. This bar 38 is disposed in a horizontal manner and is capable of being rigidly supported by bracket 32 and stove panel 18 and supports condiment receptacles 24.

Lamp support 21 is a metal stamping with the portion of either side flanged rearwardly at 41 in order to conceal the back portions thereof from view. A portion of the center of support 21 is flanged rearwardly at 42 to define an aperture, the top of such central flange serving as a resting place for a lamp shade 22. Near the bottom of support 21 are downwardly extending lugs 43 which are seated in the cutaway portions 31 of clock support 19. Directly below these lugs 43 is hole 29 which is aligned with a hole in clock support 19 and receives a stove bolt 44 for securing support 21 to support 19. A part of the upper portion of support 21 is channeled at 46 to provide guides for receiving vertical portions of the lamp shade 22. Integral with support 21 is a bracket 47 which extends forwardly at right angles to support 21 and is provided with a hole 48 for receiving a lamp socket 49 which is, after installation, provided with a suitable light bulb 50. An ordinary electrical wire 51 is provided for supplying power to switch 52, clock 20, and bulb 50.

It has been assumed that a stove or cabinet involving this invention will, in the great majority of cases, be positioned with its back against a wall when the stove or cabinet is installed for

use, and it is with this installation in mind that this specification has stated that the stove and parts of the utility supporting members conceal connections and other members from view. Many of the connections will, of course, be visible as viewed directly from the back, which is, however, the uncommon approach to the stove or cabinet.

It will be noted that practically each and every part which comprises this invention is adapted for removability or for easy assembly.

While the structures and methods disclosed herein may be considered as illustrating a perfected form and application of the principles of invention, there is no intention to limit the invention to anything less than is fairly to be considered within the scope of the appended claims.

I claim:

1. In combination with a cabinet having a frame, a backguard, a panel having a flange and slot connection with said backguard, and a supporting bracket attached to the frame and engaging said panel to maintain the flange and slot connection of the panel and backguard.

2. In combination with a cabinet having a raised back portion, a support member rigidly secured at a lower portion to said cabinet and extending above the top of said cabinet, and a panel interfitted with a portion of said cabinet and arranged to support accessory items, the upper portion of said supporting member being in engagement with said panel to maintain the panel in position and said interfitting portions being concealed behind the raised back portion of said cabinet.

3. In combination with a cabinet, a pair of supporting members, one of said members being rigidly connected to the back of said cabinet, the other of said members being loosely interfitted with a rear portion of said cabinet and held in place between said cabinet portion and said first member, and means rigidly connecting said members.

4. In combination with a cabinet, a pair of accessory supporting members associated with the rear of said cabinet, one of said members having a lower portion secured to said cabinet by removable fastening means, the other of said members being concealed behind and loosely interfitted with said cabinet, said members being readily dismountable from said cabinet and each other without affecting the structural strength of the cabinet.

5. In combination with a stove, a panel interfitted with a portion of said stove, and a bracket rigidly attached to another portion of said stove and extending into engagement with said panel adjacent the point of interconnection of the stove and panel to maintain their relationship, said interconnection being concealed by said stove.

6. In combination with a cabinet having a backguard, an accessory supporting member fastened to the back of said cabinet and free of said backguard, and another accessory supporting member adapted to rest against said first member and be held in place by said accessory supporting member and by lugs engaging said backguard, whereby said members are readily dismountable from said cabinet without affecting the structural strength of the cabinet or the finished surface of the backguard.

7. In combination with a cabinet having a backguard with a concealed flange, a supporting member rigidly supported from the rear of said

5 cabinet, said member having a vertical flange integral therewith, an accessory supporting member having slots, said accessory supporting member being supported on said vertical flange, said slots being engaged with the flange on said backguard, whereby said accessory supporting member is readily mountable and dismountable at will without altering the front surface of said cabinet.

8. In combination with a cabinet having a

backguard, an accessory supporting member rigidly secured to the back of said cabinet, and a second accessory supporting member freely supported by said first member, said second member having a slot for female relation with a concealed portion of said backguard for being held in place thereby.

5

HERBERT E. MILLS.
